CIRCUIT BREAKER

Winfield A. Atwood, Yeadon, Pa., assignor to
General Electric Company, a corporation of
New York

Application April 25, 1935, Serial No. 18,138

12 Claims. (Cl. 200—116)

My invention relates to circuit breakers, more particularly to circuit breakers of the trip-free type in which the circuit controlling contacts are manually operable between open and closed circuit positions and are automatically operable to open circuit position upon the occurrence of predetermined abnormal current conditions, and has for an object the provision of a circuit breaker of this type which is simple and reliable in its operation and inexpensive to construct.

It has heretofore been proposed to provide circuit breakers of this general type with suitable explosion-proof, arc extinguishing devices so as to combine the protective features of a fuse and the advantages of a manually operable switch, and such circuit breakers have found considerable application in the control of distribution and feeder circuits. When applied to the control of circuits of this type, especially in industrial applications, the circuit breaker is often required to carry normal currents of considerable magnitude and to interrupt extremely large currents in case a fault or short circuit occurs in the system. The circuit breaker must therefore be provided with conducting and interrupting elements of considerable size and the circuit breaker operating mechanism must be strong and rugged, which necessitates the use of heavy operating springs.

The necessity for a rugged operating mechanism and consequently a rugged supporting arrangement is augmented by the desirability of employing multipole circuit breakers in installations of this type, the circuit breaker usually being provided with a single operating mechanism for opening and closing all of the circuits. Much is yet to be desired in a circuit breaker of this type which is strong and rugged enough to withstand the severe operating conditions encountered and which will quickly interrupt currents of considerable magnitude without loud explosions or destructive arcing. Accordingly, it is a further object of my invention to provide a heavy duty circuit breaker of this type which is strong and rugged in its construction and reliable in its operation.

In carrying out my invention in one form, I provide a circuit breaker comprising relatively movable contacts and an operating mechanism therefor which includes a manually operable mechanism of rugged construction for moving the contacts between open and closed circuit positions with a snap action, and current responsive means including a normally latched tripping arm biased by suitable tripping springs for operating the contacts to open circuit position upon the occurrence of abnormal current conditions. More specifically, I provide a multipole circuit breaker comprising a base having walls extending substantially the length thereof to form individual pole compartments, and a crosswall inter-

mediate the ends of each compartment. Conductor bars secured to the base so as to reinforce the same extend from the opposite ends of each compartment to the crosswall and a movable bridging member is arranged to span the crosswall for controlling the main circuit through each pole of the circuit breaker. Each bridging member carries an arcing contact arranged to provide an intermediate shunt circuit therefor, and each pole circuit of the circuit breaker includes an arc extinguishing device of the compression chamber type, the relatively reciprocal contacts of which are connected in parallel circuit relation with the bridging member and the intermediate shunt circuit when the circuit breaker is in closed circuit position. A manually and automatically operable mechanism is also provided, which is arranged to operate all of the bridging members, the intermediate shunt contacts and the reciprocal contacts between open and closed circuit positions in predetermined sequence to prevent arcing at the main bridging contacts and to cause the final circuit-breaking action to take place within the explosion-proof compression chamber.

For a more complete understanding of my invention, reference should now be had to the drawings in which Fig. 1 is a plan view of a circuit breaker embodying my invention, the cover of the circuit breaker and certain parts thereof being removed to show the operating mechanism; Fig. 2 is a sectional view taken along line 2—2 of Fig. 1; Fig. 3 is a detailed sectional view taken along line 3—3 of Fig. 2; Fig. 4 is a plan view of the insulating support shown in Fig. 3 with the compression chamber removed; Figs. 5 and 6 are fragmentary sectional views of the operating mechanism of the circuit breaker in different operating positions; Fig. 7 is a fragmentary end view partly in section of the circuit breaker operating mechanism; and Fig. 8 is a detailed view in exploded perspective of the circuit breaker operating mechanism.

Referring now to the drawings, I have shown my invention in one form as applied to a multipole circuit breaker comprising a base 10 of molded insulation provided with a pair of side walls 11 and with a plurality of intermediate walls 12, 13 and 14 arranged to form a plurality of conductor receiving compartments extending lengthwise of the base. Each of the walls 12 extends from the uppermost end of the circuit breaker as viewed in Figs. 1 and 2, to a point adjacent one of a pair of bearing blocks 15, the purpose of which will be fully set forth later; each of the walls 13 extends from one of the bearing blocks 15 to a point adjacent a unitary trip device indicated generally by the reference numeral 16, and each of the walls 14 extends from the lowermost end of the circuit breaker to a point adjacent the other side of the trip device 16. It will be observed

that the trip device 16, the construction and operation of which will be fully described later, includes a subbase 17 provided with a pair of walls 18 arranged substantially in alignment with the walls 13 and 14. Intermediate the ends of each conductor receiving compartment, I provide a crosswall 19 formed integrally with the base 10.

Each conductor receiving compartment is provided at its opposite ends with the terminal members 20 and 21 respectively and the arrangement of the conductor members and the circuit controlling contacts for completing an electric circuit therebetween being the same in each compartment, only one such arrangement will be described.

Extending from the terminal member 20 along the base 10 to the crosswall 19, I provide a conductor bar 22 which is rigidly fastened to the base 10 in any suitable manner, as by the screws 23 adjacent the opposite ends thereof, and connected to the terminal member 20 by a bolt 24. Disposed on the opposite side of the crosswall 19 and extending therefrom along the base 10 to the trip device 16, is a second conductor bar 25 also rigidly fastened to the base, as by the screws 26 and 26a adjacent the opposite ends thereof. It will be observed that the trip device 16 includes a pair of conductors 27 and 28 which are respectively connected to one end of the conductor bar 25 by the screw 26a and to the terminal 21 by a bolt 29. The respective ends of the conductor bars 22 and 25 which are disposed adjacent the cross-wall 19 are provided with contact portions 30, and a movable bridging member 31 carrying cooperating contact portions 32 is arranged to span the crosswall 19, the contact portions 30 and 32 being preferably formed of silver or some other suitable low resistance material.

The main current circuit for each pole of the circuit breaker extends from one of the terminals 20 through one of the conductor bars 22, the associated bridging member 31, one of the conductor bars 25 and through the trip device by way of the conductors 27 and 28 to one of the terminals 21, and it will be observed that the conductor bars 22 and 25 are arranged to reinforce and strengthen the base 10.

Each of the bridging members nests within the legs of a U-shaped carrier 33 formed on one arm of a bifurcated lever 34, and is supported by a bolt 35 extending therethrough, a plurality of springs 36 being arranged in aligned recesses in the bridging member and the carrier to provide uniform contact pressure. In order to reduce blistering and arcing at the silver contacts 30 and 32, each bridging member is provided with an arcing tip or contact 37 secured to one end of a conducting spring 38 mounted in a slot 39 in the carrier 33 and secured thereto by a rivet 40. As shown, the end of the spring 38, remote from the tip 37 is electrically connected to the conductor bar 25, and the tip 37 is arranged to engage the conductor bar 22 to provide a shunt circuit around the bridging member 31, the conducting spring 38 being arranged so that when the bifurcated lever 34 is operated to move the bridging member to its open circuit position, the tip 37 will not be disengaged from the conductor bar 22 until after the contacts 30 and 32 have separated, and when the bridging member is moved to its closed circuit position, the contacts 30 and 32 will not engage until after the tip 37 has engaged the conductor 22.

In order to provide for the interruption of heavy currents without loud explosions or arcing,

each pole of the circuit breaker is provided with an arc extinguishing device connected in parallel circuit relation with the bridging member 31, which device is preferably of the type described and claimed in a copending application of Ludwig S. Walle, Serial No. 4,448, filed February 1, 1935, which application is assigned to the same assignee as the present invention. For the purposes of the present invention this arc extinguishing device may be described as comprising a cylinder 41 which forms the body portion of a compression chamber and which is secured in any suitable manner, as by the screws 42 (Figs. 3 and 4), to an insulating support 43 which is fastened to the conductor bar 22 by a plurality of screws 44.

Within the cylinder 41 is disposed a cylindrical liner 45 of kerosene-free fiber surrounding a fixed contact 46 and a reciprocal contact 47. The fixed contact 46 is electrically connected to the conductor bar 22 by means of an L-shaped conductor 48, one leg of which is rigidly fastened to the conductor 22, and the fixed contact 46 is insulated from the cylinder 41 by a plurality of insulating bushings 49 and 50 and an insulating washer 51. It will be apparent that when the nut 52 is tightened down on the threaded end of the fixed contact 46, the insulating members 49, 50 and 51 will be wedged tightly together by an enlarged shoulder 53 formed on the fixed contact 46 and by a wedge-shaped flange 54 on the cylinder 41 to form a gas-tight closure for the fixed contact end of the cylinder and to form a rigid support for the fixed contact. A sealing washer 55 preferably formed of soft copper is provided surrounding the enlarged portion 53 of the fixed contact, which washer will be tightly wedged into engagement with the cylindrical liner 45 to assist in gas-tightly sealing this end of the cylinder 41.

The movable contact end of the cylinder 41 is provided with a cylindrical cap 56 which threadedly engages the cylinder 41 and is provided with a sealing gasket 57. Supported by the cap 56, is a plug 58 in which the movable contact 47 is slidably journaled and which is provided with a skirt portion 59 for directing such gases, if any, as escape along the movable contact 47 during movement of the contact to its open circuit position, away from the bridging member 31 and the contacts associated therewith. In order to provide for snap action of the movable contact 47 while at the same time substantially sealing the compression chamber formed by the cylinder 41 and its end closures, I provide a pair of sealing washers 60 of leather or other suitable material. Further sealing means, for gas-tightly sealing the compression chamber when the movable contact 47 is in its open circuit position, are provided by a shoulder 61 formed on the movable contact 47 and arranged to engage a valve seat 62 in the end cap 56. Threadedly connected to the extending end of the movable contact 47, is an extension 63 which is electrically connected by a flexible conductor 64 to the conductor bar 25.

It will be observed that the relatively reciprocal contacts 46 and 47 of the arc extinguishing device are connected in parallel circuit relation with the bridging member 31 and the intermediate shunt circuit comprising the arcing tip 37, and in order that the final circuit-breaking action may take place within the compression chamber so as to prevent arcing at the bridging member, the other arm of the bifurcated operating lever 34 is connected to the reciprocating contact 47 by means of a resilient lost-motion connection which includes a pin 65 carried by the

bifurcated lever and extending through a slot 66 in the extension 63, a suitable spring 67 being arranged within the extension 63 with its respective ends bearing against the movable contact 47 and the pin 65.

As hereinbefore mentioned, it is desirable that the final circuit-breaking action shall occur within the compression chamber and accordingly, the lost-motion connection between the bifurcated operating lever 34 and the reciprocating contact 47 is so proportioned that when the bifurcated lever 34 is moved between open and closed circuit positions, the circuit through the compression chamber will be opened subsequent to the intermediate shunt circuit through the arcing tip 37 and will be closed prior to the closing of the intermediate shunt circuit.

It will be remembered that the bridging member circuit, the intermediate shunt circuit and the compression chamber circuit are identical in each conductor receiving compartment of the circuit breaker and in order that all of the poles of the circuit breaker may be simultaneously operated by a single operating mechanism, I provide an insulated crossbar 68 which extends across the three poles of the circuit breaker and is journaled in the before-mentioned bearing blocks 15. Each of the bifurcated members 34 is provided with a clamping portion 69 which encircles the crossbar 68 and is tightly clamped thereto by means of screws 70.

Arranged in one of the conductor receiving compartments adjacent the crossbar 68, a rugged operating mechanism is provided for operating the crossbar and all of the contacts associated therewith between open and closed circuit positions with a snap action. As may be seen best by reference to Fig. 8, this operating mechanism comprises a U-shaped frame 71 which is supported on the conductor bar 25 and fastened thereto in any suitable manner. Pivotaly mounted on a pin 72 carried by the frame 71 is an operating element 73 provided with an insulating operating handle 74 arranged to extend through a suitable aperture 75 in the circuit breaker cover 76. The operating element 73 nests within the U-shaped frame 71 and is provided with the portion 77 extending laterally therebeyond.

Connected between the extending portions 77 of the operating element 73 and an operating pin 78 the arrangement and function of which will be more fully described, is a pair of overcenter spring devices each of which comprises a U-shaped member 79 pivotally connected to the pin 78, and a yoke member 80 pivotally engaging one of the extending portions 77. A pair of plunger rods 81 which are supported by the yoke 80, slidably extend through apertures in the end of the U-shaped member 79 and carry a bearing plate 82 nested between the legs of the member 79. Each plunger rod 81 is surrounded by a compression spring 83 the opposite ends of which respectively bear against the end of the U-shaped member 79 and the plate 82. It will be observed that the plate 82 is guided by the legs of the member 79 and that the compression springs 83, which are arranged to resist relative movement between the member 79 and the yoke 80, act as an extremely strong tension spring connected between the pin 78 and the extending portions 77. Although I have shown only two plunger rods 81 for each overcenter device, it will be apparent that any suitable number of plungers and springs may be employed to obtain the desired pull.

In heavy duty circuit breakers of this type, the operating mechanism should be arranged to provide a contact pressure of considerable magnitude at the end of the closing stroke and accordingly, I prefer to employ an operating mechanism of the general type described and claimed in a copending application of Charles H. Hill, Serial No. 18,127, filed April 25, 1935, which application is assigned to the same assignee as the present invention.

This operating mechanism, in the embodiment here shown includes in addition to the operating element 73 and the overcenter spring devices, a pair of spaced parallel arms 84 pivoted on the pin 72 and connected together intermediate their ends by a cross member 85, the adjacent ends of the arms 84 opposite from the pin 72 carrying the above-mentioned operating pin 78, the respective ends of which extend through slots 86 in the frame 71 and are engaged by the overcenter spring devices. Connected between the operating pin 78 and one of the bifurcated operating levers 34 is a toggle comprising a link 87, one end of which engages the bifurcated lever 34 and the other end of which is pivoted to a second link 88 which is pivotally supported on a pin 89 and provided with a slot 90 through which the operating pin 78 extends. The link 88 as shown is a substantially triangular or three-point link and acts as a crank to make and break the toggle when the operating pin 78 is moved by the overcenter spring devices. As shown in Fig. 7, suitable cylindrical spacers 90a are provided for centering the link 88 relative to the frame 71, and preventing the link from sliding axially of the pin 89.

In Fig. 2, the circuit breaker is shown in the closed circuit position, and it will be apparent that when the operating handle 74 is moved downwardly to its lowermost position in a direction toward the trip device 16, the overcenter spring devices will be carried overcenter relative to the pivot 72 by the operating element 73 and will accordingly actuate the operating pin 78 carried by the arms 84, with a snap action to the position shown in Fig. 5, thereby moving the crank lever 88 about its pivot 89 to break the toggle and move the crossbar 68 and the circuit breaker contacts connected thereto to open circuit position. Similarly, the circuit breaker may be closed by moving the operating handle 74 in a direction away from the trip device 16 to its uppermost position, the overcenter spring devices being effective when carried overcenter thereby to operate the crank lever 88 to the closed circuit position shown in Fig. 2.

The circuit breaker is also adapted for automatic operation to open the circuit upon the occurrence of predetermined abnormal current conditions and accordingly, the operating mechanism is provided with a pivoted tripping member 91 and a pair of tripping springs 92 the operation of which is controlled by the trip device 16 in a manner to be more fully described. The trip device 16 includes a latch 93 arranged normally to engage a latch finger 94 carried by one end of the tripping member 91, the other end of the tripping member 91 being pivotally supported on the pin 72. Intermediate its ends the tripping member 91 is provided with a pin 95, each extending end of which carries a bearing plate 96 arranged to engage one end of one of the tripping springs 92 the opposite ends of which rest in countersunk depressions 97 in the

conductor bar 25. Each bearing plate 96 carries a guide rod 98 which extends through the associated tripping spring 92 into a hole 99 which extends through the conductor bar 25 and into the base member 10.

In the normal closed circuit position of the circuit breaker, shown in Fig. 2, it will be seen that the cross member 85 which extends between the parallel arms 84 is engaged by an extending portion 100 on the tripping member 91. Upon the occurrence of abnormal current conditions, the latch 93 of the trip device 16 will be moved in a manner to be fully described, to release the latch finger 94 whereupon the tripping springs 15 92 will quickly move the tripping member 91 about the pivot 72 in a clockwise direction as viewed in the drawings to the position shown in Fig. 6, thereby moving the arms 84 and the operating pin 78 carried thereby to the toggle breaking position shown in Fig. 6 against the force exerted by the over-center spring devices, to move the crossbar 68 and the circuit breaker contacts connected thereto to open circuit position.

25 In order to reclose the circuit breaker after an automatic operation to open circuit position, it is necessary first to move the handle 74 from the position shown in Fig. 6 to the position shown in Fig. 5, the operating element 73 to which the 30 operating handle 74 is fastened being provided with a portion 101 which is arranged to engage a cooperating portion 102 on the tripping member 91, to return the tripping member to the latched position shown in Fig. 5. The circuit 35 breaker contacts may now be closed by moving the handle 74 to its uppermost position shown in Fig. 2 as hereinbefore described.

Any suitable trip device may be provided for releasably latching the tripping member 91 in 40 its normal position against the bias exerted by the tripping springs 92 and for releasing the tripping member upon the occurrence of abnormal current conditions. The force exerted by the tripping springs 92, however, is of considerable 45 magnitude and accordingly, I prefer to use a rugged trip device of the type described and claimed in a copending application of John L. Lappin Serial No. 4,659, filed February 2, 1935, entitled "Circuit breakers" which application is 50 assigned to the same assignee as the present invention.

This trip device which has been previously referred to as including the subbase 17 and the spaced walls 18, may be described for the purposes of the present application as comprising a frame supported centrally of the subbase 17 having a pair of spaced walls 103 between which are supported a latch plate 104 pivoted at 105, a U-shaped impact member 106 pivoted at 107 55 and a U-shaped reset member 108 pivoted at 109. The latch plate 104 carries the previously referred to latch 93, and the yoke portion of the U-shaped impact member 106 is overturned to provide a striking surface 106a for engaging a portion of the latch plate to impart a hammer-like blow thereto. Each leg of the impact member 106 carries a pin 110 extending through a slot in one of the supporting walls 103 and arranged to engage a cam finger 111 provided on 60 the U-shaped reset member 108, the yoke portion of which is interposed in the path of the tripping member 91. The impact member 106 is normally held in the position shown in Fig. 2 by a pivoted trip bar 112 which extends across the 65 three conductor receiving compartments of the

circuit breaker and is normally biased by the spring 113 into engagement with a finger 114 carried by the impact member.

Associated with the conductors in each conductor receiving compartment of the circuit breaker are a thermal and a magnetic device for moving the trip bar 112 about its pivot to release the impact member 106. Each thermal device comprises a bimetallic element 115, one end of which is fastened to and adapted to be heated 10 by a heater strip 116, the ends of which are respectively connected to the previously referred to conductors 27 and 28. The other end of the bimetallic element 115 is arranged adjacent an adjustable insulating button 117, and adapted to 15 engage the button to move the trip bar 112 about its pivot upon the occurrence of an overload current of sufficient magnitude and duration to flex the bimetallic element.

Each of the magnetic devices comprises a U- 20 shaped magnetic member 118 which partially encircles the conductor 28 so that a magnetic flux will be induced in the member 118 upon the flow of current through the conductor. Arranged adjacent the U-shaped magnetic members 118 25 is a common armature 119 which extends across the three conductor receiving compartments and is provided with an extending finger 120 arranged to engage the pivoted trip bar 112 to move the same upon the occurrence of a sufficiently high overload in one or more of the circuit breaker poles to cause the armature to be attracted by one or more of the U-shaped magnets 118.

It will be apparent that upon the occurrence 35 of abnormal current conditions, the trip bar 112 will be moved either by the thermal or by the magnetic means, depending upon the character of the abnormal condition, to release the impact member 106 for operation by suitable biasing 40 springs 121 to strike the latch plate 104 a hammerlike blow and release the tripping member 91. When the tripping bar 91 is moved to tripping position by the tripping springs 92, the U-shaped reset member 108 will be released for operation by suitable resetting springs 122 (Fig. 1) to cause the cam fingers 111 to engage the pins extending from the U-shaped impact member 106 in order to return the impact member to its 50 normal position.

While I have shown a particular embodiment of my invention, it will be understood, of course, that I do not wish to be limited thereto since modifications may be made and I, therefore, contemplate by the appended claims to cover any 55 such modifications as fall within the true spirit and scope of my invention.

What I claim as new and desire to secure by Letters Patent of the United States, is:

1. A circuit breaker comprising a base formed 60 of molded insulation material having wall portions extending substantially the length thereof to form a conductor receiving compartment, a crosswall intermediate the ends of said compartment, terminal members adjacent the respective 65 ends of said compartment, rigid conductor bars arranged in said compartment extending along said base from each of said terminal members to said crosswall, means for securing said conductor bars to said base to reinforce the same, a movable bridging member for spanning said crosswall, said bridging member cooperating with the ends of said conductor bars adjacent said crosswall to complete an electric circuit between said terminals when said bridging member is in one pos- 70 75

tion, and means for moving said bridging member between open and closed circuit positions.

2. A circuit breaker comprising a base formed of molded insulation material having wall portions extending substantially the length thereof

5 to form a conductor receiving compartment, a crosswall intermediate the ends of said compartment, terminal members adjacent the respective ends of said compartment, rigid conductor bars arranged in said compartment fastened to said

10 base and extending therealong from each of said terminal members to said crosswall, the strength and rigidity of said conductor bars serving to reinforce said base throughout substantially the

15 entire length of the base, fixed contact members carried by said conductor bars adjacent said crosswall, a bridging member spanning said crosswall movable between open and closed circuit positions, contact portions carried by said bridging

20 member arranged to engage said fixed contacts when said bridging member is in closed circuit position, and means for moving said bridging member between said open and closed circuit positions.

25 3. A multipole circuit breaker comprising a base having a plurality of wall portions extending lengthwise thereof to form individual pole compartments and a cross wall intermediate the ends of each compartment, terminal members adjacent the respective ends of each compartment, rigid conductor bars arranged in each compartment extending along said base from each of said terminal members to said crosswall, means for securing said conductor bars to said base to reinforce said base throughout substantially the entire length thereof, movable bridging members disposed in said compartments for spanning said crosswall, each of said bridging members being arranged to cooperate with a pair of said conductor bars adjacent said crosswall to complete a circuit between said terminals in each compartment when said bridging members are in one position, and operating means for moving all of said bridging members between open and closed circuit positions.

40 4. A multipole circuit breaker comprising a base having a plurality of wall portions extending lengthwise thereof to form individual conductor receiving compartments and a crosswall intermediate the ends of each compartment, terminal members supported adjacent the respective ends of each compartment, rigid conductor bars arranged in each compartment extending along

45 said base from each of said terminal members to said crosswall, means for securing said conductor bars to said base to reinforce the same throughout substantially the entire length thereof, fixed contact members carried by said conductor bars adjacent said crosswall, a movable bridging member disposed in each of said compartments spanning said crosswalls, each of said bridging members carrying contacts arranged to cooperate with a pair of said fixed contacts to complete a circuit between said terminals in each compartment, and

50 operating means for moving all of said bridging members between open and closed circuit positions.

55 5. A circuit breaker comprising a base having wall portions extending substantially the length thereof to form a conductor receiving compartment, a crosswall intermediate the ends of said compartment, terminal members adjacent the respective ends of said compartment, conductor bars arranged in said compartment extending

60 along said base from each of said terminal mem-

bers to said crosswall, a bridging member spanning said crosswall and movable between open and closed circuit positions, said bridging member cooperating with the ends of said conductor bars adjacent said crosswall to complete an electric circuit between said terminals when said bridging member is in said closed circuit position, a compression-chamber, arc-extinguishing device provided with a pair of relatively reciprocal contacts, circuit connections for connecting said reciprocal contacts in parallel circuit relation with said bridging member, and means for operating said reciprocal contacts and said bridging member between open and closed circuit positions in predetermined sequence whereby the final circuit-breaking action occurs in said arc-extinguishing device.

6. A circuit breaker comprising a base having wall portions extending substantially the length thereof to form a conductor receiving compartment, a crosswall intermediate the ends of said compartment, terminal members adjacent the respective ends of said compartment, conductor bars arranged in said compartment extending along

25 said base from each of said terminal members to said crosswall, a bridging member spanning said crosswall and movable between open and closed circuit positions, said bridging member co-operating with the ends of said conductor bars adjacent said crosswall to complete an electric

30 circuit between said terminals when said bridging member is in said closed circuit position, means including a contact resiliently supported from said bridging member and engageable with one of said conductor bars when said bridging

35 member is in said closed circuit position for establishing a shunt circuit about said bridging member, said resiliently supported contact being arranged to maintain said shunt circuit until after

40 said bridging member is moved out of cooperating relation with said conductor bars, a compression-chamber, arc-extinguishing device provided with a pair of relatively reciprocal contacts, circuit connections for connecting said reciprocal

45 contacts in parallel circuit relation with said bridging member and said shunt circuit, and means for operating said reciprocal contacts and said bridging member between open and closed circuit positions in predetermined sequence whereby the final circuit-breaking action occurs

50 in said arc-extinguishing device.

7. A circuit breaker comprising a base having wall portions extending substantially the length thereof to form a conductor receiving compartment, a crosswall intermediate the ends of said compartment, terminal members adjacent the respective ends of said compartment, conductor bars arranged in said compartment extending along

55 said base from each of said terminal members to said crosswall, a bridging member spanning said crosswall and movable between open and closed circuit positions, said bridging member co-operating with the ends of said conductor bars adjacent said crosswall to complete an electric circuit between said terminals when

60 said bridging member is in said closed circuit position, an arc-extinguishing chamber insulatedly supported on one of said conductor bars, a fixed contact in said chamber electrically connected to one of said conductor bars, a reciprocal contact extending through a wall of said chamber for cooperation with said fixed contact,

65 said reciprocal contact being electrically connected to said other conductor bar to form a shunt circuit around said bridging member and

70 75

- 5 a common operating mechanism for moving said reciprocal contact and said bridging member between open and closed circuit position, said operating mechanism being arranged to move said bridging member to open circuit position prior to movement of said reciprocal contact to open circuit position whereby the final circuit-breaking action occurs in said arc-extinguishing chamber.
- 10 8. A circuit breaker comprising a base having wall portions extending substantially the length thereof to form a conductor receiving compartment, a crosswall intermediate the ends of said compartment, terminal members adjacent the respective ends of said compartment, conductor bars arranged in said compartment extending along said base from each of said terminal members to said crosswall, a bridging member spanning said crosswall and movable between open and closed circuit positions, said bridging member cooperating with the ends of said conductor bars adjacent said crosswall to complete an electric circuit between said terminals when said bridging member is in said closed circuit position, means including a contact resiliently supported from said bridging member and engageable with one of said conductor bars when said bridging member is in said closed circuit position for establishing a shunt circuit about said bridging member, said resiliently supported contact being arranged to maintain said shunt circuit until after said bridging member is moved out of cooperating relation with said conductor bars, an arc-extinguishing chamber insulatedly supported on one of said conductor bars, a fixed contact in said chamber electrically connected to one of said conductor bars, a reciprocal contact extending through a wall of said chamber for cooperation with said fixed contact, said reciprocal contact being electrically connected to said other conductor bar to form a second shunt circuit around said bridging member and a common operating mechanism for moving said reciprocal contact and said bridging member between open and closed circuit position, said operating mechanism being arranged to move said bridging member and said resiliently mounted contact to open circuit position prior to movement of said reciprocal contact to open circuit position whereby the final circuit-breaking action occurs in said arc-extinguishing chamber.
- 15 9. A multipole circuit breaker comprising a base having a plurality of wall portions extending lengthwise thereof to form individual pole compartments and a crosswall intermediate the ends of each compartment, terminal members adjacent the respective ends of each compartment, conductor bars arranged in each compartment extending along said base from each of said terminal members to said crosswall, movable bridging members disposed in said compartments for spanning said crosswall, each of said bridging members being arranged to cooperate with a pair of said conductor bars adjacent said crosswall to complete a circuit between said terminals in each compartment when said bridging members are in one position, arc-extinguishing chambers disposed in each compartment, a pair of relatively reciprocal contacts associated with each of said chambers, means for connecting each pair of said reciprocal contacts in parallel circuit relation with one of said bridging members, and means for operating all of said pairs of reciprocal contacts

and said bridging members between open and closed circuit positions in predetermined sequence whereby the final circuit breaking action in each compartment occurs in said arc-extinguishing chambers.

10. A multipole circuit breaker comprising a base having a plurality of wall portions extending lengthwise thereof to form individual pole compartments and a crosswall intermediate the ends of each compartment, terminal members adjacent the respective ends of each compartment, conductor bars arranged in each compartment extending along said base from each of said terminal members to said crosswall, movable bridging members disposed in said compartments for spanning said crosswall, each of said bridging members being arranged to cooperate with a pair of said conductor bars adjacent said crosswall to complete a circuit between said terminals in each compartment when said bridging members are in one position, arc-extinguishing chambers disposed in said compartments and insulatedly supported adjacent said conductor bars, each of said chambers containing a fixed contact electrically connected to a conductor bar and a reciprocal contact extending through a wall thereof, each of said reciprocal contacts being electrically connected to another conductor bar to form a shunt circuit in each compartment in parallel circuit relation with said bridging members, and a single operating mechanism for moving all of said bridging members and said reciprocal contacts between open and closed circuit position, said mechanism being arranged to move said bridging members to open circuit position prior to said reciprocal contacts, whereby the final circuit breaking action occurs in said arc-extinguishing chambers.

11. In a circuit breaker having a movable contact, an operating mechanism therefor comprising a movable operating member, overcenter spring means for operating said contact between two positions with a snap action when said operating member is moved relative thereto comprising a pair of relatively movable members respectively operatively connected to said operating member and to said movable contact, one of said members comprising a frame and the other of said members comprising a yoke, a plurality of spaced parallel plungers carried by said yoke slidably journaled in a wall of said frame, a bearing plate carried by the portion of said plungers within said frame and compression springs surrounding said plungers with the adjacent opposite ends thereof respectively engaging said frame wall and said plate.

12. In a circuit breaker having a movable contact, an operating mechanism therefor comprising a pivoted operating member, overcenter spring means for operating said contact between two positions with a snap action when said operating member is moved about its pivot comprising a pair of relatively movable members respectively operatively connected to said operating member and to said contact, one of said members comprising a U-shaped frame and the other of said members comprising a yoke, a plurality of spaced parallel plungers carried by said yoke slidably journaled in the end of said U-shaped frame, a plate carried by the portions of said plungers within said U-shaped frame, the legs of said U-shaped frame serving as guides for said plate, and compression spring means disposed about said plungers between said plate and said end of said U-shaped frame.
